UNITED STATES PATENT OFFICE.

LESTER M. WENTLING, OF FOXBURG, PENNSYLVANIA, ASSIGNOR OF ONE-EIGHTH TO RAYBURN REICHART, OF PARKERS LANDING, PENNSYLVANIA; ONE-EIGHTH TO DONALD G. JORDAN, OF ST. PETERSBURG, PENNSYLVANIA; ONE-EIGHTH TO JAMES WENTLING AND ONE-EIGHTH TO ALBERT L. NEVEL, BOTH OF FOXBURG, PENNSYLVANIA. AND ONE-FOURTH TO C. E. HARRINGTON, OF KITTANNING, PENNSYLVANIA.

ATTACHMENT FOR WELL-DRILLING TOOLS.

Application filed March 14, 1923. Serial No. 625,052.

To all whom it may concern:

Be it known that LESTER M. WENTLING, a citizen of the United States of America, residing at Foxburg, in the county of Clarion 5 and State of Pennsylvania, has invented new and useful Improvements in Attachments for Well-Drilling Tools, of which the following is a specification.

The object of the invention is to provide 10 a device, commonly known as a "cracker," for interposition between the tool employed in drilling a well and the wire cable of the spudding mechanism, so that the shock due to the impact of the tool in drilling will be 15 absorbed in the device and not transmitted to the cable with the consequent liability of disengaging the bull wheels, derrick pulleys, beams, etc., connected with the drilling mechanism. It is common practice to inter- 20 pose a piece of manila rope between the wire cable and the tool and the device herein-disclosed is intended as a simple, cheap and highly efficient substitute for the rope.

With this general purpose in view the invention consists in a construction and combination of parts of which a preferred embodiment is shown in the accompanying drawings, wherein:—

Figure 1 is a central vertical sectional view of a tool embodying the invention.

Figure 2 is a similar view, on an enlarged scale, of the lower end of the tool.

Figure 3 is a section on the line 3—3 of Figure 2.

Figure 4 is a section, on an enlarged scale, on the plane indicated by the line 4—4 of Figure 1.

Figure 5 is a section on the line 5—5 of Figure 2.

Figure 6 is a detail perspective view of one of the elements of the split bushing.

The shock absorbing elements of the device comprise a plurality of spaced washers 1 and interposed springs 2 and 3 of which 45 the latter is smaller than the former and preferably wound reversely of the same, so that the springs 3 are enlosed by the springs 2. Obviously, these springs are of the compression variety and if necessary the springs 50 2 and 3 may be replaced each pair by a single spring if the latter is of sufficient strength

for the purposes intended, which might be the case in certain drilling operations. The springs and washers are loosely mounted on a drill rod 4 the upper end of which carries 55 an exteriorly threaded conical plug 5 for engagement in a corresponding socket carried at the extremity of the wire cable leading to the spudding mechanism, the rod being enlarged, as indicated at 6, to provide a 60 fixed collar. The rod 4 and its associated spring are housed in the tubular member 7 which at the upper end is interiorly threaded for the reception of the lower end of a sleeve member 8 which is reduced as indicated at 9 and exteriorly threaded for engagement with the interior threads of the casing, the sleeve being shouldered as indicated at 10 for abutting engagement with the upper end of the casing and constituting 70 a head bearing for the journal portion 11 of the rod. The sleeve 8 is socketed at the upper end and interiorly threaded for the reception of a reduced exteriorly threaded end 12 of a thimble 13 and in the bottom of 75 the socket carries a packing ring 14 which is held securely in place by the extremity 12 of the thimble. This arrangement is provided to exclude sand and moisture from the journal portion of the rod. The thimble at 80 the upper end is recessed and receives a packing ring 15 for a similar purpose to the packing 14, the collar 6 of the rod abutting the upper end of the thimble. The tubular casing 7 at the lower end is socketed and 85 interiorly threaded as indicated at 16 for the reception of the upper end of the shank of the drilling tool, the socket 16 being of complementary construction to the threaded portion 5 of the rod, so that a plurality of 90 the devices may be used if conditions warrant it or good practice so dictates.

The combined length of the springs 2 and 3 when expanded and their interposed washers is less than the length of the casing, so that longitudinal movement of the rod 4 in the casing is provided until impact or abutment of the uppermost washer 1 with the lower end of the reduced portion 9 of the sleeve is effected, so that after the impact 100 of the tool in the drilling operation it and the tubular member 7 may rise a limited

distance without imparting bending or buckling movement to the wire cable. On the raising of the tool by the spudding mechanism, the shock on the same is absorbed by the springs 2 and 3 upon impact of the uppermost washer with the reduced portion 9, the lifting of the tool on the raising movement of the spudding mechanism not taking place until the engagement of the upper washer 1 with the reduced end of the sleeve 8.

Adjacent its lower end, the rod 4 is formed with a reduced portion 17 for the reception of a split bushing 18 constituting two complementary sections, the split bushing is exteriorly tapered as indicated clearly in Figure 2 and is surrounded by an interiorly tapered sleeve 19 by which the bushing is brought into firm contact with the reduced portion 17. A washer 20 is carried by the lower extremity of the rod 4 and is peripherally reduced as indicated at 21 to provide a boss effecting abutting engagement with the lower end of the split bushing, thus spacing the remaining portion which is in the nature of a flange from the lower end of the sleeve 19 which is formed with diametrically disposed axially arranged exteriorly threaded studs 22 which pass through corresponding eyes formed in the flange portion of the washer and receive the nuts 22 on the opposite side of the washer from the boss 21. A washer 23 abuts the nuts 22 and is held in place by a castle nut 24 which is engaged by a cotter pin 25 extending through a diametrical hole or perforation 26 formed in the lower threaded extremity 27 of the rod 4. The springs and their attendant washers are thus retained on the rod 4 by the sleeve 19 and its attendant devices and the shock transmitted to the springs on the raising operation of the drilling tool is transmitted to the sleeve and through it to the split bushing thus bringing the latter into firm contact with the reduced portion 17 of the rod. The strains of these operations are thus transmitted to the shoulder formed by the reduced portion 17 with the lower end of the rod and are not imparted to any screw thread connection which would likely break due to crystallization of the parts. Also, the construction at the lower end of the rod by means of which the springs and washers are retained thereon will permit the ready removal of the parts for the replacement of any springs or the addition of other or further shock absorbing elements. The tubular casing 7, just at the top of the lower socketed end 16 is provided with downwardly inclined openings or apertures 28 through which water or other liquid accumulations in the casing may be ejected to prevent such accumulations rising in the casing with the possible consequent damage to the operative parts of the device.

Having described the invention, what is claimed as new and useful is:—

1. A device for the purpose indicated comprising a tubular casing, a rod slidably mounted in said casing, a split bushing mounted on the rod adjacent the lower end, a sleeve in surrounding relation to said bushing, the latter being exteriorly tapered and the former interiorly tapered, means for securing the sleeve to the lower extremity of the rod, and cushioning elements bearing upon the sleeve and adapted to cushion the weight of the casing.

2. A device for the purpose indicated comprising a tubular casing, a rod slidably engaged in said casing, a plurality of compression springs surrounding the rod, washers slidably mounted on the rod and interposed between the compression springs, a split bushing mounted on the rod adjacent the lower end, and means for securing said bushing in place and constituting a thrust for said compression springs.

3. A device for the purpose indicated comprising a tubular casing, a rod slidably engaged in said casing, a plurality of compression springs surrounding the rod, washers slidably mounted on the rod and interposed between the compression springs, a split bushing mounted on the rod adjacent the lower end, said split bushing being exteriorly tapered, a sleeve in surrounding relation to said bushing and interiorly tapered and provided with axially arranged studs at its lower end, a thrust washer engaging said bushing and provided with eyes for the reception of said studs, nuts engaged with the studs and abutting the washer, and means carried by the rod and engaging the nuts to prevent recession of the latter.

4. A device for the purpose indicated comprising a tubular casing, a rod slidably engaged in said casing, a plurality of compression springs surrounding the rod, washers slidably mounted on the rod and interposed between the compression springs, a split bushing mounted on the rod adjacent the lower end, said split bushing being exteriorly tapered, a sleeve in surrounding relation to said bushing and interiorly tapered and provided with axially arranged studs at its lower end, a thrust washer engaging said bushing and provided with eyes for the reception of said studs, nuts engaged with the studs and abutting the washer, the lower end of the rod being exteriorly threaded, a washer carried by said threaded end and abutting the nuts, a castle nut engaged with the threaded end and abutting the washer, and a cotter pin inserted transversely through the rod and engaging the castle nut.

In testimony whereof he affixes his signature:

LESTER M. WENTLING.
